**FURNITURE ASSEMBLY COMPOSED OF SEVEN
INTERRELATED ARTICLES****Robert J. Olsen, 11 Waverly Place,
New York, N.Y. 10003****Filed Apr. 13, 1970, Ser. No. 22,401****Term of patent 14 years****Int. Cl. D6—05****U.S. Cl. D6—4**

T1 Q.1.

T1 Q.2.

FIG. 1 is a perspective view of a furniture assembly composed of seven interrelated articles showing my design;

FIG. 2 is an exploded view thereof;

FIG. 3 is a perspective view of one section serving as a hassock;

FIG. 4 is a perspective view of another section serving as a low-backed seat;

FIG. 5 is a perspective view of a combination of two sections serving as a high-backed chair;

FIG. 6 is a perspective view of a combination of two sections serving as a lounge;

FIG. 7 is a perspective view of a combination of two sections serving as a high-backed stool;

FIG. 8 is a perspective view of a combination of two sections functioning as a couch; and

FIG. 9 is a perspective view of a section serving as a pad.

I claim:

The ornamental design for a furniture assembly composed of seven interrelated articles, as shown and described.
